COMBINATION LOCK

Frederic K. Heyer, Stamford, Conn., assignor to
The Yale & Towne Mfg. Co., Stamford, Conn.,
a corporation of Connecticut

Application December 5, 1933, Serial No. 700,995

35 Claims. (Cl. 70—285)

This invention relates to combination locks, and more especially to combination locks adapted for use on lockers or cabinets.

A feature of my invention is the arrangement of a combination lock in which there is possible a dual operation of the bolt mechanism by rotary combination tumblers, and by key operated mechanism, the operation being dual in so far as it pertains to the operation of the bolt mechanism through a single bolt retracting cam.

In connection with this dual operation, a further feature of the invention is embodied in the arrangement of the mechanism so that the bolt may be retracted by the key mechanism and thrown by the tumbler mechanism.

A further feature of my invention is embodied in the arrangement of means for automatically and positively dispersing the combination as the bolt mechanism is thrown into a fully locked position.

An important feature of my invention embodies means whereby an actuator is connected to the bolt operating means for retracting and then projecting the bolt, this connection being maintained until the bolt is substantially thrown. This feature is of importance especially in a dead bolt lock. An auxiliary feature is the control of the tumblers over this connection, so as to require the setting up of the combination.

While I will show in my drawings a particular embodiment of my invention and will explain in the specifications its detailed construction, it should be understood that I believe my invention to be relatively broad in scope, and that I feel myself entitled to broad claims covering a relatively wide field of equivalents.

I shall now refer to the drawings wherein Fig. 1 is a view of the bottom of the lock casing showing the bolt and cam mechanism therein. Fig. 2 is a view similar to Fig. 1 showing in addition the combination disperser and the tumbler fence in position. Fig. 3 is a further view along the lines of Figs. 1 and 2 showing the tumbler operating cam in its operating position, and the cam fence in its position relatively thereto. Fig. 4 is drawn along the lines of Fig. 3 but shows the cam fence in outward relation to the cam member and the bolt in locked position. Fig. 5 is a view along the lines of Fig. 3 showing the mechanism when the bolt is partially withdrawn. Figs. 5A, 5B, 5C and 5D are various views showing the relation of the cam fence and the tumbler fence to the disperser and tumbler mechanism.

Fig. 6 illustrates the operation of the bolt by the key operated mechanism and Fig. 6A is a view

similar to Fig. 6 showing the parts of Fig. 6 in a slightly different position with the bolt throwing cam moving in a bolt throwing direction. Figs. 7A and 7B are respectively side and elevation views of the bottom half of the lock casing.

Figs. 8A and 8B are respectively side and elevation views of the bolt of my invention. Figs. 9A and 9B show side and elevation views of the bolt operating cam of my invention and its relation to the central tumbler carrying post. Figs. 10A and 10B show elevation and side views of the disperser member. Figs. 11A and 11B show elevation and side views of the tumbler fence. Figs. 12A and 12B show side and elevation views of the tumbler actuator fence. Figs. 13A and 13B show side and elevation views of the tumbler supporting member for anchoring the tumblers relatively to the casing. Figs. 14A and 14B show side and elevation views of a tumbler forming a portion of my invention. Figs. 15A and 15B illustrate an actuator washer which is located relatively to the tumbler of Fig. 14 for determining the combination thereof. Figs. 16A and 16B show side and elevation views of a washer adapted to occupy a position between tumblers. Figs. 17A and 17B show top and sectional views of the tumbler operator. Figs. 18A and 18B show side and elevation views of the top plate of the lock casing. Fig. 19 is a perspective view of the bolt throwing spring while Fig. 20 is a view of a spring utilized in connection with a lock having key operating mechanism.

Fig. 21 shows my lock assembled relatively to a locker or cabinet with the bolt in thrown position and the combination dial and key actuated mechanism attached to the front thereof. Fig. 22 is drawn partially in section along the lines 22—22 of Fig. 21 and illustrates the method of changing the combination while the lock is attached to the locker casing. Figs. 23A and 23B are taken along line 23A—23A of Fig. 23 and show the relation of the combination maintaining stud in its two positions. Fig. 23 is a sectional view of the assembly of the combination dial relatively to the front plate of the lock and the tumbler operating cam, and shows the key operated clutch mechanism. Figs. 24 and 25 illustrate more in detail the operation of the clutch mechanism.

Fig. 26 is a view of the lock with the top plate assembled relatively thereto and showing the tumbler operating cam. Fig. 27 is a bottom view of the mechanism of Fig. 23. Fig. 28 is a view of the key utilized in connection with the mechanism of Fig. 23. Figs. 29 and 29A illustrate the construction of

the combination maintaining stud whose operation is best shown in Figs. 23, 23A, and 23B.

Referring now more particularly to the drawings and especially to Figs. 7A to 20 inclusive, I 5 will indicate first the component portions or parts of my lock mechanism which are adapted to lie in the lock casing 10 shown particularly in Figs. 7A and 7B. The lock casing 10 has a pair of ears 11 drilled at 12 for screws whereby the casing may 10 be fastened to a door. The casing is cut out at points 13 for the positioning of the lugs 14 of the top plate member 15 shown in Figs. 18A and 18B. A hole 16 in the casing 10 has a screw threaded 15 outside abutment 17 and is utilized for the purpose of changing the combination as will be described more in detail later.

In Figs. 8A and 8B there is shown the bolt 18 having the nose 19, and adapted to slide in the casing 10 and to be guided by the lugs 20 and 21 integral with the bottom of the casing. For operating the bolt, there is provided a bolt operating member 22 (Figs. 9A and 9B) which is integral with the tumbler supporting shaft 23 and has a bolt operating portion 24 adapted to fit into 25 the cut-out portion 25 of the bolt for operating the bolt as will be readily understood. The lower end 26 of the post 23 is adapted to rest in the bore 27 at the bottom of the lock casing 10 shown in Fig. 7B.

30 The bolt operating member 22 is also equipped with a post 28 upon which is adapted to be pivoted the tumbler fence member 29 shown in Figs. 11A and 11B, this member having a spring 30 which cooperates with the lug 31 on the bolt operating member 22 for constantly urging the tumbler fence 29 in a counter-clockwise direction about its pivot on the shaft 28, and in a direction tending to bring it against the periphery of the tumblers as will be more particularly indicated later in the specification.

40 In Figs. 12A and 12B there is shown the tumbler actuator fence member 32 which has a bearing at 33 whereby it also may be mounted on the pin 28 of the bolt operating member 22 and superimposed on the tumbler fence member 29. The spring 34 of this actuator fence 32 cooperates with an upstanding lug 35 on the tumbler fence 29 so as to urge the fence 32 in a clockwise direction and away from the periphery of the tumblers and the tumbler actuator 45 as will be later indicated. A pin 36 on the under-face of the cam fence 32 is adapted to rest in a cut-out portion 37 of the tumbler fence 29 so as to prevent clockwise movement of the actuator fence 32 relatively to the tumbler fence 29 beyond the point where the pin 36 will come solidly against the end surface of the cut-out portion 37. It will readily be observed that because of the relation between the pin 36 and the cut-out portion 37, the ordinary movement of the tumbler fence 29 in a counter-clockwise direction, will serve to move the fence 32 in the same direction, while, should the fence 32 be held against its usual movement in a clockwise direction, the tumbler fence 29 will itself be free to move in a clockwise direction leaving the actuator fence 32 behind.

In Figs. 13A and 13B there is illustrated a member 38 having a sleeve portion 39 upon which are supported the tumblers 40 shown in Figs. 14A and 14B; also the actuator members 41 shown in Figs. 15A and 15B, and the washer members shown in Figs. 16A and 16B. The assembly of these tumblers, washers, and actuators, on the member 39 is conventional, but the member 38 is rather unique in that once the tumblers are mounted on

its sleeve 39, the upper portion of the sleeve is staked over as at 43, so as to hold the tumblers assembled on the sleeve 39, the pin 44 of the member 38 being then adapted to enter the hole 44a at the bottom of the casing 10 so as to hold 5 the tumblers securely in assembled relation to the lock casing.

For rotating the tumblers, I prefer to utilize a tumbler actuator 45 shown more particularly in Figs. 17A and 17B, this member having a pin 46 10 which cooperates with one of the actuators 41 shown in Figs. 15A and 15B, for imparting rotary movement to the topmost tumbler which in turn imparts like movement to the next tumbler, etc. as will be readily apparent to those skilled in the 15 art. The actuator 45 is notched as at 47 for the entry of the nose 32a of the actuator fence 32 as will be quite clear. In addition, the actuator 45 has the cut-out portions 48 which are adapted to permit the entry of tongues protruding from the 20 combination dial whereby the cam may be rotated by the combination dial mechanism.

In Figs. 10A and 10B, I illustrate a disperser member 50 whose function and operation is most novel and will be referred to presently.

25 Referring now more particularly to Fig. 1, the dead bolt member 18 is shown in its fully thrown position wherein it is deadlocked by the surface 24 of the bolt operating member 22 cooperating with the bolt surface 25a, the member 22 being 30 in turn maintained in this deadlocking position by the spring 49 of Fig. 19, as will be readily apparent.

Referring now to Fig. 2, the bolt is shown again in a fully thrown position, and the disperser 50 35 of Figs. 10A and 10B is shown spring pressed in a counterclockwise direction by its spring 51 cooperating with the lug 31 of the bolt operating member 22. The counter-clockwise rotation of the disperser 50 is limited by a stop pin 52 cooperating with the downward lug 53 integral with the disperser. The disperser has also an integral upstanding lug portion 54 and a shoulder portion 55 whose functions will be described later in the specification.

45 Referring now to Fig. 4, the bolt 18 is once again shown in its fully projected position, the tumbler fence member 29 is shown in the locked position of Fig. 2, and the actuator fence member 32 is shown mounted on its pivot 28 and superimposed on the tumbler fence 29. As is readily apparent, the spring 34 of the actuator fence 32 acts to urge the same in a clockwise direction relatively to the fence 29 with which the spring 34 cooperates, and away from the surface of the periphery of the tumbler actuator 45 which is shown superimposed on the tumblers and in tumbler operating position. The tumbler fence 29 is in turn pressed in the direction of the tumbler surfaces by spring 30. It is held 60 slightly away from the tumbler surfaces by the actuator fence 32 which is pressed by fence 29 through pin 36 against the actuator 45 and through this pin 36 limits the movement of fence nose 29b, so as to prevent its touching the tumbler peripheries. This relation is important and is fully taken advantage of as will be shown later. The normal position of the upstanding lug 54 and the shoulder portion 55 of the disperser member 50 relatively to the cam fence 32 are also shown 65 in Fig. 4.

70 Fig. 3 shows the parts of Fig. 4 when the combination has been set and the nose 32a of the fence 32 has entered the actuator gating 47 coincidentally with the entry of the nose 29b of the 75

tumbler fence 29 into the gatings 40a of the tumblers 40, all of course under pressure of the spring 30. It will be quite obvious that in the position of the parts in Fig. 3, it will be possible to obtain 5 a coupled rotation of the actuator 45, the fence 32, the tumbler fence 29, the tumblers 40, and therefore the bolt operating member 22 whose pin 28 supports both the actuator and tumbler fences. This rotation of the parts is fully illustrated in 10 Fig. 5 which shows the bolt partially retracted.

It will be readily seen that with the bolt in the position of Fig. 5, the face 29a of the tumbler fence member 29 will abut the surface 10a of the casing 10. This will naturally tend to rotate the 15 fence member 29 about its axis on the pivot 28 of the bolt operator 22, so as to withdraw the nose 29b of the tumbler fence entirely from the gatings 40a of the tumblers 40.

It will be apparent that this movement is 20 against the pressure of spring 30 of the fence member 29. It will also be apparent that there will be a tendency for the actuator fence 32 to move with member 29, especially since the fence 32 is normally spring pressed away from the actuator 45 by its spring 34. Means must therefore be provided for maintaining the fence nose 32a in the actuator gating 47 in order that further control over the bolt operator 22 through its pin 28 be retained. Such means form part of disperser member 50 and will appear presently.

The disperser member 50 is so arranged that while it allows for control of the bolt operator 22 it takes advantage of the outward movement of the nose 29b from the aligned tumbler gatings 35 40a to thereafter maintain the nose 29b out of the gatings so as to permit rotation of the tumblers relatively to the tumbler fence 29, which acts to offset the nose 29b relatively to the aligned tumbler gatings and thus disperses the combination 40 in a commercially desirable manner. It will be recalled that the disperser member 50 is spring pressed to rotate in a counterclockwise direction relatively to the post 23 as is illustrated in Fig. 2, due to the pressure of its spring 51 against the 45 lug 31 of the bolt operator 22. This counterclockwise movement, as will be remembered, is limited by the pin 52. It will be understood that as the parts move from the position of Fig. 3 to the position of Fig. 5, the disperser is also 50 moved against the said spring pressure, being impelled by the nose 29b of the fence member 29. As soon as the nose 29b is withdrawn from the aligned tumbler gatings to its position in Figs. 5A and 5C the shoulder portion 55 of the disperser 55 50 will tend to spring against the nose 29b as is shown in Fig. 5A, thus acting to maintain the fence nose 29b out of the gatings 40a of the tumblers 40 in the same relation for instance as illustrated in Fig. 5D. The Figs. 5A and 5C illustrate this movement of the disperser.

As was already indicated, ordinarily, should the fence member 29 swing outwardly in the direction indicated in Figs. 5A, 5C and 5D, it would carry with it the actuator fence 32. However, the 65 fence member 32 is so mounted that its nose 32a is maintained positively within the gating 47 of the cam member 45 by the action of the disperser 50 as will now be indicated. The fence pin 36 is so related to the cut-out portion 37 of the tumbler fence 29, as was previously emphasized, that when the actuator fence nose 32a is solidly against the periphery of the actuator 45, the tumbler fence nose 29b is not in contact with the tumblers. In other words, there is a slight advance of the nose 70 75 29b of tumbler fence 29 over the nose 32a of

actuator fence 32, not sufficient, however, to permit appreciable entrance of the fence 32 into gating 47 until the fence nose 29b enters the tumbler gatings 40a.

Therefore, when the nose 29b is being moved 5 out of the aligned gatings 40a, this movement is considerably in advance of the movement of the nose 32a from the actuator gating 47, so that when the nose 29b is entirely outside the tumbler gatings 40a and the disperser member 10 15 20 25 30 35 40 45 50 moves upwardly to insure its maintenance outside the gatings, the nose 32a is still within the gating 47. The movement of the disperser 50 whereby it brings its portion 55 against the nose 29b of fence 29, is capable also of simultaneously moving the upstanding lug portion 54 into position to cooperate with a downwardly extending lug 54a on the actuator fence 32, and thereafter the fence 32 will be maintained with its nose 32a within the gating 47 of the tumbler operator 45 until the bolt is fully retracted, and from then on until the bolt is in a practically fully thrown position. This relation of the upstanding lug 54 of the disperser with the downward lug portion 54a of the actuator fence 32 is illustrated 20 25 30 35 40 45 50 55 60 65 70 75 80 85 90 95 100 105 110 115 120 so that the fence 32 is allowed to move freely to the position of Fig. 4 under the impelling force of its spring 34. This position is reached by the member 32 just before the fully thrown position of the bolt 18 is reached, the bolt being then in a position however to be actuated by the spring 49 acting on the portion 24 of operator 22 to throw the bolt forcefully into a deadlocked position with the portion 25a deadlocked against the part 24 of the operator. This last movement moves the operator 22 and both the actuator fence and tumbler fence relatively to the actuator 45 and the tumblers 40 and makes it necessary to reset the combination in order to once again retract the bolt.

The sequential operation of the parts so far described may be indicated as follows: Rotation of the cam member 45 is adapted to align the tumbler gatings 40a and the gating 47 of the actuator 45 opposite the noses 29b and 32a respectively of the tumbler fence 29 and the actuator fence 32. This alignment of the gatings and fences, forms an integral connection between the actuator 45, the fence members 29 and 32, the bolt operator 22 and the bolt 18, so that the bolt may be moved to a fully retracted position by rotation of the parts in a clockwise direction from the position of Fig. 3 to the position of Fig. 5 and beyond until the bolt 18 is fully retracted. This movement of the parts acts, through cooperation of the surface 29a of the fence member 29 with the surface 10a of the casing, to withdraw the nose 29b from the aligned gatings.

35. This outward movement of the fence nose 29b, is taken advantage of by the disperser 50 which is forced by the spring 51 in a counter-clockwise direction so that its shoulder 55 moves relatively to nose 29b as illustrated in Fig. 5C to maintain the nose in its position illustrated in Fig. 5A wherein the fence 29 will be maintained out of the aligned tumbler gatings. At the same time, the upstanding lug portion 54 of the disperser 50 will jump in behind the downward depending lug 54a of the fence 32 and will act to maintain the fence in the position of Fig. 5B with the nose 32a in engagement with the gating 47 of the actuator 45, so that there will be maintained an operating relation between the fence 32, actuator 45 and bolt operating member 22, necessary to impart outward movement to the bolt 18.

Thereafter, counter-clockwise rotation of the actuator 45 to throw the bolt will leave the tumblers behind so as to disperse them relatively to the tumbler fence 29. Further rotation in a counter-clockwise direction will operate to bring the disperser 50 and its lug 53 against pin 52, thus preventing further counter-clockwise rotation of the disperser 50, so that the continued rotation of the actuator 45 and fence member 32 in a counter-clockwise direction will permit the separation of the depending lug 54a from the upstanding lug 54 of the disperser and will allow the spring 34 to move the fence 32 out of the gating 47 of the actuator 45. It will also release the tumbler fence member 29. This operation takes place just before the bolt has reached a fully thrown position, which fully thrown position will then be imparted to it by the action of the spring 49 against the upstanding cam part 24 of the bolt throwing lever 22.

In Figs. 6 and 6A I illustrate the operation of the bolt 18 by a key operated mechanism which actuates directly the bolt operator 22 by means of the shaft 23. The operation of this key

operating mechanism will be illustrated later in this specification, but it is sufficient for the description of Figs. 6A and 6 to indicate that the key operated mechanism rotates the shaft 23 without the intermediary of the tumbler mechanism. This rotation of the shaft 23 simply carries with it the bolt operating cam 22 and the nose 24 thereof which cooperates with the cut-out slot 25 in the bolt 18 for actuating the same. It is quite clear that the operation is simple and direct and that the bolt may be thrown or retracted without any incidental operation of the tumbler mechanism.

It is interesting to note that if the parts are left in the position of Fig. 6 with the bolt retracted, it is unnecessary to operate the shaft 23 directly through the key operated mechanism, but that it is possible in the position of the parts in Fig. 6 to throw the bolt by rotation of the actuator 45 by the combination setting dial. The operation is best illustrated in Fig. 6A. It will be noted that the gating 47 of the actuator 45 is practically in a vertical position in Fig. 6. Rotation in a counter-clockwise direction will gradually bring the gating 47 into the position it occupies in Fig. 6A wherein the nose 32a of the fence 32 will be adapted to enter therein. This movement of the fence 32 is possible because the pressure of the spring 60 is sufficient to overcome the pressure of the fence spring 34 tending always to swing the member 32 in a clockwise direction. It is quite obvious that in this position of the parts, the upstanding lug 54 of the disperser 50 enters behind the depending lug 54a of the fence 32 to maintain its nose 32a in the cam gating 47.

It will be readily appreciated that rotation of the actuator 45 in a counter-clockwise direction from the position of Fig. 6A will cause the entire assembly to move in the same direction until the parts reach the position just prior to that illustrated in Fig. 2 with the stop member 53 of disperser 50 against the lug 52 of the casing. Thereafter, counter-clockwise rotation of the fence 32 with the actuator 45 will act to release the lug 54a from the upstanding lug 54 of the disperser so that the member 32 may move to its position of Fig. 4 and so that the spring 49 may complete the full throw of the bolt 18 and bring it into a deadlocking position relatively to the portion 24 of the bolt operator 22.

Referring now more particularly to Figs. 21 to 29 inclusive, I will describe the feature of my invention which relates to the changing of the combination while the lock is attached to the door. I will also describe the mechanism which permits the ready key operation of the central shaft 23 when such operation is desired. The construction of the dial and the particular means for operating the central shaft through the key mechanism are all part of the invention of Karl A. Brauning, Serial No. 652,140 filed January 17, 1933, and per se form no part of this invention.

The lock casing 10 is secured through means of the ears 11 and bolts 61 and nuts 62, to the surface of a door 63. On the outer surface of the door 63, there is secured the main base plate 64 bearing the usual indicator relatively to which the combination dial 65 is rotated.

The dial 65 is retained relatively to the plate 64 by the shoulder 66 of the knob 67. The knob in turn is maintained in assembled relation to the plate 64 through means of the spring ring 68, all of which is shown clearly in Fig. 23. In order to rotate the dial 65 together with the member 75

67, a peculiar type of mutilated stud 69 is used. This stud is carried by the knob 67 and has a portion 70 which is adapted to ride into any one of a series of scalloped portions 71 in the dial member 65 as is clearly shown in Figs. 23A and 5 23B. It will be readily understood that when this portion 70 of the stud 69 is in one of the scalloped portions 71 as is best shown in Fig. 23B, the dial 65 must rotate with the knob member 67. 10 However, when the stud 70 is rotated so that its mutilated portion 72 is opposite one of the scallops 71 as in Fig. 23A, the knob 67 may rotate relatively to the dial 65 so that the combination relation between the dial 65 and the knob 67 15 may be altered.

Therefore, in order to change the combination, the abutment 17 built up on the back of case 18, is utilized. The screw threaded member 73 may be removed from the abutment as is best shown 20 in Fig. 22, thus permitting a screw driver 74 to be inserted through the hole 16, and into the stud 69. This stud 69 is particularly constructed as shown in Figs. 29 and 29A with a bevelled inclined side 70a, so that pressure of the screw driver will 25 readily find the adjustment slot 70b, whereupon the stud may be rotated to its position of Fig. 23A and the combination changed. Then, the stud may be rotated to the position of Fig. 23B relatively to the dial 65 and the combination secured 30 in the changed position. Naturally, the combination may only be changed when the door is in an open position, so that its manipulation is only possible by those knowing the combination, and therefore, authorized to change it.

35 For operating the tumbler actuator cam 45 I utilize a member 77. This member 77 is mounted for integral movement with the knob member 67 so that the two prongs 78 which are adapted to enter the cut-out portion 48 of the actuator 45, 40 will normally make the knob 67 operative to set the combination in the usual way as is disclosed in the Brauning application already referred to. A further member 79 is secured against endwise movement relatively to the member 77 and has a 45 downward extending portion 80 equipped with a rib 81 adapted to cooperate with the cut-out portion 82 of the central operating shaft 23. However, this portion 80 has no rotating connection with the knob 67 under ordinary circumstances 50 so that the rotation of the knob 67 does not affect the part 80 and it remains in a fixed relation to the shaft 23 because of the rib connection 81—82.

However, whenever it is desired to operate the central shaft 23 by key rather than by combination, anyone possessing the key of Fig. 28 may 55 operate the key plug 83 of a usual cylinder lock. Preferably, the knob 67 may itself form the cylinder part of the lock. The plug 83 has a cam portion 84 best shown in Figs. 24 and 25, which 60 cam portion is adapted to effect an operative engagement between the knob 67 and the operating portion 80. For effecting this operation there are mounted about the cam member 84, a pair of clutch members 85 and 86, normally kept by a 65 spring 87 in close engagement with the cam 84 as is best shown in Fig. 24. The inner portion of the member 80 is serrated as at 88 for cooperation with teeth 89 on the clutch members 85 and 86. It will be quite obvious that when the cam member 70 70 84 of the cylinder 83 is rotated to its position of Fig. 25, the teeth 89 will have been forced into engagement with the serrated surface 88 of the member 80 and the cam 84 will not be allowed to rotate further relatively to the cylinder lock 75 83, so as to form a fixed clutching engagement

between the various parts. It will be quite apparent that under these circumstances, there will be a fixed rotation of the elements 67, 83, 84, 85 and 80, adapted to rotate the shaft 23 and the bolt operator 24.

5

I claim:

1. In a combination lock, a bolt, a bolt operating member, a series of tumblers having gatings, an actuator for rotating said tumblers, a tumbler fence member cooperable with said tumblers and 10 adapted to enter their gatings when aligned, an actuator fence adapted to engage said actuator as said tumbler fence member enters the tumbler gatings, and means whereby said actuator fence is thereafter operable to actuate said bolt operating member to retract and throw said bolt.

2. In a combination lock, a bolt, a bolt operating member, a series of tumblers having gatings, an actuator for rotating said tumblers, a tumbler fence member cooperable with said tumblers, and 20 adapted to enter their gatings when aligned, an actuator fence adapted to engage said actuator as said tumbler fence member enters the tumbler gatings, and means of connection between said actuator fence and said bolt operating member 25 whereby when the actuator fence is engaged with said actuator, the rotation of said actuator will actuate said bolt operating member.

3. In a combination lock, a bolt, a rotary bolt operator for retracting and throwing said bolt, a 30 series of rotary tumblers having gatings, an actuator for rotating said tumblers to align their gatings, an actuator fence and a tumbler fence mounted on said bolt operator, means for connecting said actuator fence with said actuator as 35 said tumbler fence enters the aligned tumbler gatings, whereby rotation of said actuator thereafter will retract and project said bolt.

4. In a combination lock, a bolt, a bolt operating member, a series of tumblers having gatings, an actuator for rotating said tumblers to align said gatings, an actuator fence for actuating said bolt operating member and itself adapted to engage said actuator for operation thereby, a 40 tumbler fence arranged to enter said tumbler gatings when they are aligned, and means whereby said tumbler fence and said actuator fence are interconnected for entrance into their respective gatings.

5. In a combination lock, a bolt, an operator 50 member having a cam for moving said bolt, a tumbler fence member carried by said operator member, an actuator fence carried by said operator member, a series of tumblers, an actuator for rotating said tumblers and having a gating for 55 cooperation with said actuator fence whereby to form an operating chain with said fence and the bolt operator for operating said bolt, said actuator fence and said tumbler fence being movable respectively into the actuator gatings and into the aligned tumbler gatings, the actuator and its fence being then rotatable to actuate the bolt operator to withdraw the bolt, means whereby said tumbler fence is removed from the aligned tumbler gatings when said bolt is retracted, means for 60 maintaining it in its removed position, means for locking said actuator fence within the actuator gating, and means whereby said actuator fence is released from the actuator gating as said bolt is fully thrown.

6. In a combination lock, a bolt, an operator member having a cam for moving said bolt, a tumbler fence member carried by said operator member, an actuator fence carried by said operator member, a series of tumblers, an actuator for ro- 70 75 75

- tating said tumblers and having a gating for co-operation with said actuator fence whereby to form an operating chain with said fence and the bolt operator for operating said bolt, said actuator fence and said fence being movable into the tumbler gatings and said actuator gatings when said gatings are properly aligned, the actuator and its fence being then rotatable to actuate the operator member to withdraw the bolt, means whereby said tumbler fence is removed from the aligned tumbler gatings when said bolt is retracted, disperser means adapted simultaneously to lock said tumbler fence outside the tumbler gatings and said actuator fence within the actuator gating, and means whereby said disperser releases both said fences as said bolt is thrown whereby it becomes necessary to reset the tumblers and fences to regain control over said bolt operating member.
20. 7. In a combination lock, a bolt, an operating member for retracting said bolt, a post on said member, a series of tumblers mounted on said post, means controlled by said tumblers for moving said operating member to retract said bolt, and means for rotating said post and moving said operating member to retract the bolt independently of said tumblers and the means controlled thereby.
8. In a combination lock, a bolt, an operating member for retracting said bolt, a post integral with said operating member, a series of tumblers having gatings and loosely mounted for free rotation about said post, means for setting said tumblers to align the gatings, a fence member adapted to enter the gatings, means connecting the fence member to said operating member whereby to retract said bolt when said tumblers are set and subsequently rotated, and key actuated means adapted to rotate said post independently of said tumblers and fence so as to actuate said operating member to retract the bolt.
9. In a combination lock, a series of tumblers and actuators, a removable sleeve member about which said tumblers and actuators are assembled, means for securing said tumblers and actuators against movement off said sleeve member while permitting their free rotation thereon, and means secured to said sleeve member in offset relation thereto for maintaining said sleeve member against rotation in said lock.
50. 10. In a combination lock, a casing, a sleevelike member, a series of tumblers mounted on said sleevelike member, means retaining said tumblers in stacked relation on said sleevelike member so that said tumblers may be inserted and removed from said casing as a unit with said sleevelike member, and nesting means on said casing adapted to receive said sleevelike member and tumblers and to hold said sleevelike member against rotation with said tumblers while permitting free endwise removal of said sleevelike member and tumblers.
11. In a combination lock, a casing, a sleevelike member, a series of tumblers mounted on said sleevelike member, means retaining said tumblers in stacked relation on said sleevelike member so that said tumblers may be inserted and removed from said casing as a unit with said sleevelike member, nesting means on said casing, said 65. 70. 75. 80. 85. 90. 95. 100. 105. 110. 115. 120. 125. 130. 135. 140. incidental setting up of the combination tumblers.

17. In a combination lock, a bolt, key operated means for retracting and projecting said bolt, 5 said key operated means being arranged to permit removal of the key when the bolt is retracted, combination tumblers in said lock having the usual gatings, an actuator for rotating said tumblers to align the gatings, a fence adapted to enter said aligned gatings, means movable to form a connection between said actuator and bolt when said fence moves into the tumbler gatings whereby the bolt may be retracted and projected independently of said key operated means, said means 10 being so positioned when the bolt is retracted by said key means as to engage said actuator upon idle rotation thereof, whereby to throw said bolt from its retracted position without the incidental setting up of the combination tumblers.

20 18. In a combination lock, a bolt, an operator for retracting and throwing said bolt, an actuator fence for moving said operator to retract and throw said bolt, an actuator having a gating into which said fence fits whereby rotation of said 25 actuator moves said fence to actuate said operator, means whereby said fence is impelled to leave said actuator gating at a point just before said bolt member reaches a fully thrown position, combination tumblers and a tumbler fence, means 30 whereby said tumblers and tumbler fence prevent the entry of said actuator fence into said actuator gating until said tumblers are properly aligned relatively to said tumbler fence, and a spring means arranged to become effective at 35 said point for fully throwing said bolt from that point to a fully thrown position whereby said fence is dispersed relatively to said actuator gating.

30 19. In a combination lock, a bolt, a bolt operating member, a series of tumblers having gatings, 40 an actuator for rotating said tumblers to align said gatings, an actuator fence for actuating said bolt operating member and itself adapted to engage said actuator for operation thereby, a tumbler fence adapted to enter said tumbler gatings when they are aligned, means whereby said fences are interconnected to enter their respective gatings together, means for forcing said tumbler fence out of said tumbler gatings as said bolt is retracted, means for releasing said actuator fence 45 from engagement with said actuator just before said bolt reaches a fully thrown position, and a spring for thereafter fully throwing said bolt.

50 20. In a combination lock, a bolt, a rotary bolt operator for retracting and throwing said bolt, a series of rotary tumblers having gatings, an actuator for rotating said tumblers to align their gatings, an actuator fence and a tumbler fence mounted on said bolt operator, means for connecting said actuator fence with said actuator when said tumbler fence enters the aligned tumbler gatings whereby rotation of said actuator will retract and project said bolt, the entry of said tumbler fence into said gatings being a prerequisite to the connection of said actuator fence with the actuator, means whereby said tumbler fence is locked out of the tumbler gatings as said bolt is retracted, and means whereby said actuator fence is released from said actuator and back into the control of said tumbler fence just before said bolt reaches a fully thrown position, and a spring means for thereafter fully projecting said bolt.

55 21. In a combination lock, a bolt, an operator member having a cam for moving said bolt, a

tumbler fence carried by said operator member, an actuator fence carried by said operator member, means whereby said actuator fence is controlled in its movement by said tumbler fence, a series of tumblers, an actuator for rotating said tumblers and having a gating for cooperation with said actuator fence whereby to form an operating chain with said actuator fence and the bolt operator for operating said bolt.

60 22. In a combination lock, a bolt, an operator member having a cam for moving said bolt, a tumbler fence carried by said operator member, an actuator fence carried by said operator member, means whereby said actuator fence is controlled in its movement by said tumbler fence, 15 a series of tumblers, an actuator for rotating said tumblers and having a gating for cooperation with said actuator fence whereby to form an operating chain with said actuator fence and the bolt operator for operating the bolt, said actuator fence and said tumbler fence being movable respectively into the actuator gating and into the aligned tumbler gatings, the actuator and its fence being then rotatable to actuate the bolt operator to withdraw the bolt.

25 23. In a combination lock, a bolt, a rotary bolt operator for retracting and throwing said bolt, a series of rotary tumblers having gatings, an actuator for rotating said tumblers to align their gatings, an actuator fence and a tumbler fence 30 mounted on said bolt operator, means for connecting said actuator fence with said actuator and said tumbler fence with the aligned tumbler gatings, whereby rotation of said actuator will retract and project said bolt, means whereby 35 said tumbler fence is withdrawn from said tumbler gatings as said actuator and fences rotate in retracting said bolt, and means whereby said actuator fence is movable into connection with the actuator under the control of said tumbler 40 fence.

45 24. In a combination lock, a dead bolt, an operator for retracting and throwing said bolt, an actuator fence for moving said operator to retract and throw said bolt, an actuator having a gating into which said fence fits whereby rotation of said actuator moves said fence to actuate said operator in both a bolt throwing and bolt retracting direction, combination tumblers and a tumbler fence, means whereby said tumblers and tumbler fence prevent the entry of said actuator fence into said actuator gating until said tumblers are properly aligned relatively to said tumbler fence, means whereby said fence is impelled to leave said actuator gating just as said bolt is moved to a nearly fully thrown position, and a spring for moving said bolt to its fully thrown position from said nearly thrown position, the said final movement of said bolt being effective to move said operator and said fence 50 relatively to said actuator gating.

55 25. In a combination lock, a bolt an operating member for moving said bolt, a series of tumblers having gatings, an actuator for said tumblers also having a gating, an actuator fence and a tumbler fence mounted on said operating member, and means whereby said fences are adapted to enter simultaneously into said actuator and tumbler gatings when said gatings are properly aligned.

60 26. In a combination lock, a bolt, an operating member for moving said bolt, a series of tumblers having gatings, an actuator for said tumblers also having a gating, an actuator fence and a tumbler fence mounted on said operating mem-

ber, means whereby said fences are adapted to enter simultaneously into said actuator and tumbler gatings when said gatings are properly aligned, whereby rotation of said actuator thereafter will move said actuator fence and the operating member to retract the bolt.

27. In a combination lock, a bolt, an operating member for moving said bolt, a series of tumblers having gatings, an actuator for said tumblers also having a gating, an actuator fence and a tumbler fence mounted on said operating member, and means whereby said fences are adapted to enter simultaneously into said actuator and tumbler gatings when said gatings are properly aligned, said actuator and tumblers and said fences being then rotatable to move said operating member and retract the bolt, and means whereby said tumbler fence is removed from the aligned gatings upon retraction of said bolt whereby reverse rotation of said actuator and its fence will rotate the said fence relatively to the tumblers while projecting the bolt.

28. In a combination lock, a bolt, an operating member for moving said bolt, a series of tumblers having gatings, an actuator for said tumblers also having a gating, an actuator fence and a tumbler fence mounted on said operating member, and means whereby said fences are adapted to enter simultaneously into said actuator and tumbler gatings when said gatings are properly aligned, said actuator and tumblers and said fences being then rotatable to move said operating member and retract the bolt, means whereby said tumbler fence is removed from the aligned gatings upon retraction of said bolt whereby reverse rotation of said actuator and its fence will rotate the said fence relatively to the tumblers while projecting the bolt, and means for projecting the actuator fence from its gating when the bolt reaches a substantially fully thrown position.

29. In a combination lock, a bolt, an operating member for moving said bolt, a series of tumblers having gatings, an actuator for said tumblers also having a gating, an actuator fence and a tumbler fence mounted on said operating member, and means whereby said fences are adapted to enter simultaneously into said actuator and tumbler gatings when said gatings are properly aligned, said actuator and tumblers and said fences being then rotatable to move said operating member and retract the bolt, means whereby said tumbler fence is forced out of said tumbler gatings as said bolt is retracted, spring means actuated by said fence movement and pressing thereafter on said actuator fence in a direction to force it out of its actuator gating, and means for maintaining said actuator fence in its gating against the force of said spring means until said actuator has been rotated so as to move said actuator fence and the operating member to position the bolt in a substantially fully thrown position.

30. In a combination lock, a bolt, an operating member for moving said bolt, a series of tumblers having gatings, an actuator for said tumblers also having a gating, an actuator fence and a tumbler fence mounted on said operating member, and means whereby said fences are adapted to enter simultaneously into said actuator and tumbler gatings when said gatings are properly aligned, said actuator and tumblers and said fences being then rotatable to move said operating member and retract the bolt, means whereby said tumbler fence is forced out of said tumbler gatings as said bolt is retracted, spring means actuated by said

fence movement and pressing thereafter on said actuator fence in a direction to force it out of its actuator gating, and means for maintaining said actuator fence in its gating against the force of said spring means until said actuator has been rotated so as to move said actuator fence and the operating member to position the bolt in a substantially fully thrown position. 10

31. In a combination lock, a dead bolt, an operator for retracting and projecting said dead bolt, a series of tumblers having gatings, a fence cooperable with said gatings, an actuator, means connected with said dead bolt operator and engageable with said actuator for actuating the operator for retracting and projecting said dead bolt, means for preventing the engagement of said first means and said actuator until said fence has entered said aligned gatings, and means for maintaining said first means in engagement with said actuator thereafter until said bolt is retracted and thereafter at least substantially projected. 15

32. In a combination lock, a dead bolt, an operator for retracting and projecting said dead bolt, a series of tumblers having gatings, a fence cooperable with said gatings, an actuator, means connected with said dead bolt operator and engageable with said actuator for actuating the operator for retracting and projecting said dead bolt, means for preventing the engagement of said first means and said actuator until said fence has entered said aligned gatings, means for maintaining said first means in engagement with said actuator thereafter until said bolt is retracted and thereafter at least substantially projected, and means whereby said tumbler fence is ejected from the tumbler gatings prior to the projection of said bolt. 20

33. In a combination lock, a dead bolt, an operator for retracting and projecting said dead bolt, a series of tumblers having gatings, a tumbler fence cooperable with said gatings, an actuator, an actuator fence connected with said dead bolt operator and engageable with said actuator for actuating the operator for retracting and projecting said dead bolt, means for preventing the engagement of said actuator fence and said actuator until said tumbler fence has entered said aligned gatings, and means for maintaining said actuator thereafter until said bolt is retracted and thereafter at least substantially projected. 40

34. In a combination lock, a dead bolt, an operator for retracting and projecting said dead bolt, a series of tumblers having gatings, a tumbler fence adapted to enter said gatings, an actuator having a gating, an actuator fence carried by said operator and adapted to enter the gating of said actuator whereby rotation of said actuator thereafter retracts and projects said dead bolt, means whereby the entry of said actuator fence into said actuator gating requires the entry of the tumbler fence into said tumbler gatings, means whereby said tumbler fence is ejected from the tumbler gatings incidental to the operation of the dead bolt by said operator, a spring urging said actuator fence out of said actuator gating thereafter, and means maintaining said actuator fence in the actuator gating against the pressure of said spring until said bolt is substantially projected. 55

35. In a combination lock, a dead bolt, an operator for retracting and projecting said dead bolt, a series of tumblers having gatings, a tumbler 60

fence adapted to enter said gatings, an actuator having a gating, an actuator fence carried by said operator and adapted to enter the gating of said actuator whereby rotation of said actuator 5 thereafter retracts and projects said dead bolt, means whereby the entry of said actuator fence into said actuator gatings requires the entry of the tumbler fence into the tumbler gatings, means whereby said tumbler fence is ejected from 10 the tumbler gatings incidental to the operation of

the dead bolt by said operator, a spring urging said actuator fence out of said actuator gating thereafter, means maintaining said actuator fence in the actuator gating against the pressure of said spring until said bolt is substantially projected, and means whereby said tumbler fence is movable with said actuator fence and relatively to said tumblers once it is ejected from the tumbler gatings. 5
